United States Patent Office.

C. C. WILLIAMS, OF BROOKLYN, NEW YORK.

Letters Patent No. 96,179, dated October 26, 1869.

IMPROVED APPARATUS FOR PRESERVING FRUIT.

The Schedule referred to in these Letters Patent and making part of the same.

To all whom it may concern:

Be it known that I, C. C. WILLIAMS, of Brooklyn, in the county of Kings, and State of New York, have invented a new and useful Improvement in Fruit-Preserving Apparatus; and I do hereby declare that the following is a full, clear, and exact description, thereof, which will enable others skilled in the art to make and use the same, reference being had to the accompanying drawing forming part of this specification.

Figure 1 is a top view of my improved apparatus.

Figure 2 is a detail vertical section of the same, taken through the line $x-x$, fig. 1.

The invention consists in certain improvements upon devices used in the preservation of fruits, and particularly that portion thereof which relates to the transmission of steam from the boiler to the jar.

A is the main part of the boiler, which I prefer to make in the shape of a truncated cone.

Around the lower part of the boiler A is formed a shallow extension, B, made continuous with the boiler A, and the top of which is made flat, to serve as a shelf to support the cans or jars while being heated, and which being filled with boiling water, assists in heating the bottoms or lower parts of the cans or jars.

The extension B is provided with an upwardly-extending flange or rim, b', to keep the cans or jars in place while being operated upon.

The boiler A may, if desired, be made without the extension B, but in this case it should be provided with a ring-shelf, fitting around the base of the boiler to receive the jars or cans.

In the top of the boiler A is formed a circular opening, which should be made large enough to receive the hand for convenience in keeping the interior of the boiler perfectly clean.

Around the opening in the top of the can is formed an upwardly-projecting flange, C, having a screw-thread formed upon its outer surface to receive the screw-thread of the cap D.

The joint between the cap D and the top of the boiler is made steam-tight, by a rubber or equivalent packing, E, placed around the flange C, and interposed between the lower edge of the cap D and the top of the boiler A.

F are radial pipes, the inner ends of which enter the cap D, and communicate with the interior of the boiler A through holes in the bottom of said cap.

The series of radial pipes F rests upon an upwardly-projecting flange, formed around the top of the boiler A, as shown in fig. 2.

Upon the ends of the pipes F are formed, or to them are attached, short tubes or sheaths G, to receive the upper ends of the pipes H, which are bent, so as to extend down along the sides of the boiler A,

and enter the jars or cans, said pipes being made of such length as to reach to the bottom of said jars or cans, and having openings in the sides of their extreme lower ends, and there only, so that the steam may be introduced into the jars or cans at their bottoms, thus insuring the contents of said jars being heated in all their parts, which is not the case when the steam is introduced higher up in said jars or cans.

The joint between the pipes F and H is made steam-tight by short rubber tubes I, placed upon the outer ends of the pipes F, and through the outer ends of which the upper ends of the pipes H are introduced into the sheath G, attached to the said pipes F.

J are plugs, connected to the top flange of the boiler A, by short chains, and which may be inserted in the outer ends of the pipes F, to prevent the escape of the steam when the pipes H are detached for convenience in placing or removing the jars or cans.

A small opening should be made in the top of the boiler A, closed with a cap or other suitable stopper, for convenience in introducing hot water, if required, during the operation of canning the fruit.

The lower part of the boiler A may be provided with a stop-cock, a', for convenience in drawing off water when desired.

In using the apparatus, it is set upon the top of a range, kitchen-stove, or upon a gas or oil-stove, as may be most convenient.

The cans or jars, previously filled with the fruit or other substance for preserving, are arranged upon the extension or shelf B, and the pipes introduced into them and coupled to the pipes F.

As the steam is formed, it is discharged through the openings in the lower ends of the pipes H into the jars or cans, close to their bottoms, and permeating their entire contents, speedily heats them sufficiently.

As soon as one of the cans is ready, the pipes H F are uncoupled, and the open end of the pipe F closed with one of the plugs J, allowing the jar or can to be removed, sealed, and replaced by another jar, and so on, without disturbing the process of heating the others.

In case all or several of the jars or cans are ready to be removed at the same time, the plug may be left out of the pipe F of the can first removed, allowing the steam to escape, and holding all the cans heated to the same point.

I am aware that a patent was granted to W. D. Brooks, July 2, 1867, for a machine involving the general principles of the machine above described, and therefore I lay no claim to the apparatus itself, but simply to certain improvements thereon.

Having thus described my invention,

I claim as new, and desire to secure by Letters Patent—

1. An improved boiler-apparatus, consisting of boiler proper A and steam-chest D, screwed thereon, and having a perforated bottom, as shown and described.

2. The removable steam-chest D, with apertured bottom, in combination with a series of pipes, F H,

and air-excluding sleeves G, as and for the purpose specified.

The above specification of my invention signed by me, this 9th day of August, 1869.

C. C. WILLIAMS.
